UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON HEELS.

1,135,034.

Specification of Letters Patent.

Patented Apr. 13, 1915.

Application filed February 14, 1910. Serial No. 543,670.

To all whom it may concern:

Be it known that I, THOMAS LUND, a citizen of the United States, residing at Beverly, in the county of Essex and State of Massachusetts, have invented certain Improvements in Machines for Operating Upon Heels, of which the following description, in connection with the accompanying drawings, is a specification, like reference 10 characters on the drawings indicating like parts in the several figures.

This invention relates to certain improvements in mechanism for forming a bevel or lip at the breast end of heel blanks.

15 The invention is herein represented as embodied in an attachment to a heel compressing machine of the type shown and described in United States Letters Patent No. 776,875, dated December 6, 1904, but is 20 not limited to use with machines of this type, and is shown as applied thereto merely for purposes of illustration.

An important feature of the invention consists in providing, in connection with a 25 lip-cutting knife and its actuating mechanism, a heel blank support or carrier which is sustained by a vertically moving member as, for instance, the reciprocating head of the heel compressing machine, and is automatically moved thereby into position for receiving a heel blank and also into position for presenting the blank to the knife during the reciprocations of the head. Preferably, the heel blank carrier is arranged to 30 be moved into receiving position during the downward movement of the reciprocating head, which occurs after the compressing operation, so that the ejector of the heel compressing machine will place the compressed blank on the carrier at the same time that another blank is advanced in position to be acted upon by the compressing dies, and as the reciprocating head rises a movement is also imparted to the carrier to locate 35 the compressed blank in proper position for the operation thereon of the lip cutting knife. Preferably, also, the knife is so arranged for actuation through a moving part of the machine that the power 40 which produces its cutting stroke is stored in a yielding element, as a spring or equivalent motor, by such moving part, preliminary to the operation of cutting the lip or bevel, and the knife is prevented from

acting on the blank until the latter has been 55 moved into proper position therefor by its carrier, whereupon the knife is released by a suitable tripping device and cuts the corner from the blank.

An important feature of the invention accordingly consist in so combining a heel blank support or carrier and a lip-cutting knife with a heel compressing machine that a blank will be automatically delivered to the carrier, the carrier actuated to position 60 the blank in proper relation to the knife, and the knife actuated to bevel such blank, following the action of the dies thereon so that the operations of compressing the 65 blanks and cutting the lips will be performed continuously upon a single machine in a very effective manner.

Another important feature of the invention consists in providing improved means for removing the blank from its carrier at 70 the completion of the lip-cutting operation. In the illustrated embodiment of the invention this means comprises an ejector suitably supported in a movable member which also supports an abutment or gage against which 75 the breast of the heel blank is located when the blank is in position for operation thereon by the knife. The ejector slides freely in the movable member, and an elastic device, such as a spring, forms a connection 80 between the movable member and the ejector, the movable member being caused to travel in a downward direction, through suitable actuating connections with the reciprocating head as the latter moves up and 85 while the blank carrier is moving to locate a blank sustained thereon in the path of the lip-cutting knife. Preferably the ejector is provided with an arm or extension which comes in contact with a movable stop during 90 its downward movement and holds back the ejector, thereby putting the elastic device under tension. The downward movement of said member also serves to locate the abutment or gage against the breast end of the 95 blank as the carrier is turned to bring said end into a substantially horizontal position, whereby the blank is supported against the thrust of the knife. The movable stop is connected with the knife carrier, and when 100 the knife is actuated to cut the corner from the blank the stop is removed from engagement with the arm carried by the ejector 105

and the ejector is released and acts to force the blank from its carrier.

Other important features of the invention, including improved details of construction and combinations of parts, will be hereinafter more particularly described and claimed.

In the accompanying drawings, which illustrate a preferred construction embodying the principles of the invention; Figure 1 illustrates, in vertical section, certain parts of a heel compressing machine with the present improvements applied thereto, the carrier being shown in receiving position, with a heel blank thereon; Fig. 2 is a similar view showing the same parts in another position; Fig. 3 is a rear elevation of the lip-cutting mechanism shown in Fig. 1, somewhat enlarged; and Fig. 4 is a plan view of the heel blank carrier.

In the embodiment of the invention selected for illustration, 1 indicates a part of the rigid frame of a heel compressing machine, such, for instance as that disclosed 25 in the Letters Patent above referred to, and 2 indicates the reciprocating head thereof which will be supported for free movements in suitable guideways formed in the rigid frame 1. The head 2 carries suitable dies 30 for imparting lateral compression to a heel blank as the head rises and meets a stationary die, which is carried by the rigid portion of the frame 1 over the reciprocating head and serves to impart vertical compression to the blank. The crank shaft 9, to which is imparted rotative movements by the main power shaft of the machine, carries a crank 15 provided with a crank pin 16, having connected thereto a link 10 which is 35 pivotally connected with the members 11 and 12 of a toggle. The toggle member 12 is pivotally connected at 13 to a rigid part of the frame 1, and the toggle member 11 is pivotally connected at 14 with the reciprocating head 2. From this construction it 40 will be seen that rotation of the crank shaft 9 will serve to impart reciprocating movements to the head 2, as fully described in said Letters Patent.

50 Referring now more particularly to the mechanism for cutting a lip or bevel on the breast end of a heel blank contemplated by the present invention, 5 indicates a bracket which is rigidly secured by bolts, or similar 55 fastenings, to the rear portion of the reciprocating head 2, and 18 indicates a heel blank supporting carrier, herein shown as provided with two laterally spaced, angularly disposed wings, 8, 8, which are rigid 60 with the carrier, and connected through a pivot pin 7 with the bracket 5 so as to swing freely about said pin as a center. The wings are shown as being provided with openings having cam-shaped 65 recesses or slots 31, 32 and 33 within

their edges which communicate with and are angularly disposed to each other, and pins 34, which may be provided with anti-friction rolls, extend oppositely from a rigid portion of the frame 50 into said recesses, 70 said parts being so constructed and arranged that as the head 2 rises, the cam rolls will be caused to pass from the slot 33 to the slot 31, and thence into the slot 32, which will turn the heel blank carrier from the position shown in Fig. 1, into that shown in Fig. 2. Two oppositely movable heel blank gripping jaws 20, 20, are supported upon the carrier 18, each of said jaws being, as herein shown, provided with a stem 19, 75 which plays in a transverse bore formed in the carrier, each stem having formed thereon a rack 21, and said racks are arranged upon opposite sides of and engage the teeth of a pinion 22, which is pivotally supported 80 upon the carrier. A spring 24, or other yielding device, is connected at one end to the carrier, and at its other end to one of the jaws and acts, through the connections described, with a normal tendency to urge 85 the jaws toward each other. The stems 19 have, as shown best in Fig. 4, extensions 26, which project beyond the sides of the carrier 18 and are provided with holes 27, and the jaws have supporting base portions 28 90 apertured to receive slidable pins 29 which are provided with handles and may be placed in any of the several holes to adjust the distance between the jaws for heel blanks 95 of different sizes. The outer or receiving ends of the jaws are slightly beveled, as shown in Fig. 4, and the construction of the parts just described is such that when the heel blank carrier occupies the position shown in Fig. 1 and a blank is moved between the jaws 20 the jaws will yield to receive the blank which will be gripped between them and held by the frictional engagement between the jaws and the sides of the blank, due to the action of the 100 spring 24.

A rack bar 36, which is provided with a suitable number of teeth as shown, is supported from the bracket 5 so as to be reciprocated in unison with said bracket by 115 the head 2. The bar 36 is preferably provided with suitable flanges which slide in guideways 38 formed in a frame 50, which is shown as connected with the main frame 1 of the machine by studs 40 which enter sockets in an upper part of the frame, and by a plate 52 which is bolted or otherwise suitably secured to a face portion 54, thereon. The rack 36 meshes with a pinion 42, which is shown as pivotally connected to the frame 120 50, and this pinion in turn meshes with a rack 44 formed on or carried by a reciprocating block 46, which has flanges to slide in suitable guideways 48, in the sides of the frame 50. The lower part of the block 46 125 130

has a dove-tailed groove 56 to receive the dove-tailed plate 58 which carries a projecting block 60, constituting a gage and abutment for the blank, and preferably 5 formed with a beveled rear surface, as shown. A clamping screw or bolt 62, having a thread to receive a nut thereon, passes through an aperture in the base of the block 46 and a slot in the dove-tailed plate 58. By 10 this construction the gage or abutment 60 may be adjusted in a direction parallel with the breast line of a heel blank when the blank is sustained in position against the abutment, to accord with the adjustments of 15 the knife for producing different bevels; or such abutment may be entirely removed from its supporting block and other abutments of different sizes substituted therefor in order that the machine may accommodate heel blanks of varying lengths. 20

The frame 50 is shown as having two rigid screw-threaded studs 73 projecting therefrom and said studs carry, respectively, the sleeves 75 which rigidly support a knife- 25 carrier guide 78, which is arranged at a suitable inclination to the breast line of a heel blank when sustained in position against the abutment 60, as will appear from Figs. 1 and 2. It will thus be seen that the knife, 30 which slides in said guide, may remove the corner from the blank at an appropriate bevel or inclination in the production of the lip. Each of the sleeves 75 is held adjustably upon its supporting stud by nuts 76, 35 which are in threaded engagement with the stud and bear against the opposite ends of the sleeve, whereby the sleeves, and hence the knife guide, may be adjusted in order to determine the amount of stock which 40 the knife will remove from the corner of the breast. The knife 80 projects rigidly from a knife carrier, or stem 82, which slides in the guide 78 and is shown as being formed or provided at its lower extremity with a 45 sleeve 89, through which passes a rod 94. At suitable points near the extremities of this rod are attached the ends of two strong springs 95, whose upper or opposite ends may be secured to any rigid part of the 50 frame, as for instance to the studs 104, which project therefrom. The sleeve 89 is shown as having a rigid toe 84 which extends at an angle to the knife carrier, and a suitable detent 86 which is shown as being 55 pivotally supported from a pin 88 carried in perforated ears 90 which are sustained by the knife guide, is arranged in position to engage the toe and hold the knife retracted while the actuating springs 95 are under 60 tension and ready to impart to the knife its cutting stroke. The detent 86 is shown as having a lateral projection 98, and an arm 92, pivoted to the rod 94 closely adjacent to the toe 84, has a finger 96 which is arranged 65 to engage the projection 98 when the lower

part of the arm is caused to swing from the position shown in Fig. 1 to that shown in Fig. 2 and move the detent out of engagement with the toe, thereby releasing the knife and permitting the springs 95 to 70 react and actuate the knife. The pivotally supported arm 92 is provided with a slot 100 which receives a pin or projection 102 rigid with the link 10, through which said link imparts to the arm, at the proper 75 times in each cycle of operations of the machine, first a downward movement for pulling the knife outwardly which permits the detent to engage the toe and hold the knife in readiness for action, and second a swing- 80 ing movement for tripping the knife. The manner in which these operations are performed will be more fully described hereinafter.

The numeral 64 indicates the ejector for 85 removing blanks from the carrier 18 at the completion of the lip-cutting operation. The ejector is supported for free vertical sliding movements in the block 46, and is also arranged to slide through a slot pro- 90 vided therefor in the abutment or gage 60, and is shown as having a laterally extending arm 66. A yielding device, herein shown as a spring 68, is connected at one end by a screw 70 or like fastening to the 95 arm 66, and at its opposite end by a similar fastening 71 to the block 46, and acts with a normal tendency to hold the blank-engaging end of the ejector projected a suitable distance beyond the lower surface of the 100 abutment 60, as shown in Figs. 1 and 3. A bell-crank lever 106 is fulcrumed to a pin 108 carried by the frame 50 and has its upper end so formed as to constitute a stop 105, which is arranged to intersect the path 105 of movement of the arm 66 as the ejector is moved down to position the abutment against a blank sustained upon the carrier. The lower arm of this lever is shown as hav- 110 ing a sleeved extension 110 which is pivotally connected with one end of a link 114 by a pin 112, the opposite end of this link having pivotal connection with the knife carrier through a pin 116, which projects 115 from the carrier. With this construction, prior to the operation of the knife and when it occupies the position shown in Fig. 1, the stop 105 will lie immediately below the arm 66. As the block 46 is moved down the stop will engage and arrest the move- 120 ment of the arm and hold back the ejector, and the spring 68 will be put under tension. When the knife is released and moves under the force of its springs 95 to cut the corner from the blank the described connections 125 between the knife and the stop 105 will remove said stop from engagement with the arm 66, and the spring 68 will force the ejector against the blank to eject the blank 130 from the carrier.

With the several parts of the machine occupying the positions shown in Fig. 1, the reciprocating head 2 has been lowered, following the operation of compressing a blank, and the blank has been placed by the ejector of the heel-compressing machine or blank feeding device upon the carrier 18 and between the jaws 20, and is gripped thereby. The block 46 is now in its most elevated position and the ejector 64 projects below the abutment 60, and the knife has been pulled down and the actuating springs 95 put under tension, while the detent 86 is in engagement with the toe 84 and holds the knife retracted in opposition to the force of its springs. The crank being at the extreme outward limit of its throw, when the machine starts, the link 10 is moved in a direction to straighten the toggle and raise the reciprocating head for compressing a blank between the dies, which moves upward also the heel blank carrier and its blank, the carrier being gradually turned as it rises through the action of the cam slots and roll to present the blank with its breast horizontal, as shown in Fig. 2. As the head 2 rises the rack bar 36 is caused to rotate the pinion 42 which imparts a downward movement to the block 46, causing the heel blank abutment and gage 60 to meet the breast of the blank as it rises, so as to act as a stop for the blank and support it against the thrust of the knife, and the arm of the ejector engages the stop 105 and is held back while the spring 68 is stretched and rendered in condition to act. As the link 10 is moved from the position shown in Fig. 1 to that shown in Fig. 2, the pin 102 carried thereby acts to swing the arm 92 over, and substantially at the moment when the crank has reached the inward limit of its throw the finger 96 pushes the detent over the edge of the toe 84 and the knife is released and cuts the corner from the blank. The described connections between the knife carrier and the stop 105 are so constructed and arranged that the stop is moved from beneath the arm of the ejector to release it at or about the same time that the knife completes its cutting stroke, so that the blank is ejected from the carrier immediately after the lip-cutting operation. The continued movement of the crank will cause the toggle members to lower the reciprocating head, during which the heel blank carrier will be restored to its receiving position as shown in Fig. 1, and the movements down and rearwardly of the link 10 will cause the pin 102 to engage the extremity of the slot 100 and pull down the knife carrier and knife, and also rock the lower end of the arm 92 and move the finger 96 out of contact with the detent 86, thus permitting the detent to fall by gravity in front of the toe 84 as the toe passes beyond the end of

the detent. The parts will then again occupy the positions shown in Fig. 1, and the described cycle of operations may be repeated as often as the reciprocating head makes a complete reciprocation and the compressed blanks are delivered to the carrier.

Having thus described my invention, what I claim as new and desire to secure by Letters Patent of the United States is:

1. In a machine of the class described, the combination with a knife and actuating mechanism therefor, of a reciprocating member, and a heel blank carrier supported for movements with said member and also for additional movements, first into position for receiving a blank from said member and then into position for locating the blank in the path of the knife.

2. In a machine of the class described, the combination with a knife and actuating mechanism therefor, of a reciprocating member, and a heel blank carrier supported for movements with said member and additionally movable to one position for receiving a heel blank from said member and then to a different position for locating the blank in the path of movement of the knife.

3. In a machine of the class described, the combination with a knife and actuating mechanism therefor, of a reciprocating member, and a heel blank carrier movable therewith, and means to position the carrier for receiving a blank from said member and for locating the blank in the path of movement of said knife.

4. In a machine of the class described, the combination with a knife and actuating mechanism therefor, of a vertically reciprocating head, a heel blank carrier movable therewith, and means for locating the carrier in position to receive a blank upon one movement of said head and for turning the carrier to present the blank in a different angular position for action thereon by the knife upon another movement of the head.

5. In a machine of the class described, the combination with a lip cutting knife, of a heel blank carrier arranged to receive a blank with its tread face in a substantially horizontal position, means for turning the carrier through an angular distance of substantially ninety degrees to locate the blank in the path of the knife, and means for actuating the knife to cut the blank operative when the blank reaches the last-named position.

6. In a machine of the class described, the combination with a knife, of a reciprocating head, a heel blank carrier sustained thereby, means whereby said carrier is moved to position for receiving a blank carried by the head upon one movement of said head and is moved out of said position to locate the blank in the path of the knife

upon another movement of the head, and means for actuating the knife which is not rendered operative until the carrier reaches the last-named position.

5 7. In a machine of the class described, the combination of a knife, constructed for forming a lip at the breast-end of a heel blank, an actuator therefor, a reciprocating member, a blank carrier sustained thereby and arranged for movement to carry a blank into position for operation thereon by the knife, means for storing power in the knife actuator, and means for releasing said power to cause the knife to act on the blank when the blank occupies said position.

10 8. In a machine of the class described, the combination of a knife, an actuator therefor, a blank carrier arranged for movement from position to receive a blank to position for locating the blank in the path of the knife, and means for storing power in said actuator as the carrier moves into the first-mentioned position and for releasing the power to cause the knife to act on the blank 25 when said carrier is moved into the last-mentioned position.

15 9. In a machine of the class described, the combination of a knife, an actuator therefor, a reciprocating member, a blank carrier sustained thereby and arranged for movement from a position to receive a blank to a position for locating the blank in the path of the knife, and means for storing power in said actuator as the carrier moves into 30 the first-mentioned position and for releasing the power to cause the knife to act on the blank when said carrier is moved into the last-mentioned position.

20 10. In a machine of the class described, the combination of a knife, a yielding actuator therefor, a detent for holding the knife against movement by its actuator, a carrier arranged to receive a blank in one position and to locate it in the path of the knife in a 45 different position, and means for retracting the knife and storing power in said actuator as the carrier moves into the first-mentioned position, and for tripping the detent to release the knife when the carrier is moved 50 into the last-mentioned position.

11. In a machine of the class described, the combination of a knife, a yielding actuator therefor, a detent for holding the knife against movement by the actuator, a reciprocating head, a carrier sustained by said head and arranged to be moved thereby from a position for receiving a blank to a position for locating it in the path of the knife, mechanism for reciprocating said head, and 55 means operated thereby for retracting the knife and storing power in said actuator as the carrier is moved into the first-mentioned position and for tripping the detent to release the knife when the carrier is moved 60 into the last-mentioned position.

12. In a machine of the class described, the combination of a knife, a yielding actuator connected therewith, a detent for holding the knife when retracted against movement by its actuator, a reciprocating head, a carrier sustained by said head and arranged to be moved thereby from a position for receiving a blank to a position for locating it in the path of the knife, mechanism for reciprocating said head, and an arm movably connected with said knife and mechanism and having a projection to coöperate with said detent, said parts being so constructed and arranged that the arm is caused to retract the knife against the stress of its actuator and the detent holds it retracted as the carrier is moved to receiving position, and the projection trips the detent and releases the knife when the carrier is moved to locate the blank in the path of the knife. 70 75 80

13. In a machine of the class described, the combination of a reciprocating lip cutting knife, an abutment for engaging the breast end of a heel blank to support the blank against the thrust of said knife, means for moving a blank to position it against said abutment, and means for actuating the knife. 85 90

14. In a lip-cutting machine, the combination of a knife, an abutment, means for moving a heel blank to position it with its breast end against said abutment, and means for actuating the knife to remove the corner from the blank while the blank is held against the abutment. 95 100

15. In a lip-cutting machine, the combination of a knife, an abutment, a carrier arranged to receive a heel blank in one position and to move to another position for locating the breast end of the blank against the abutment, and means for actuating the knife to remove the corner from the blank while the blank is held against the abutment. 105

16. In a lip-cutting machine, the combination of a knife, an abutment constructed and arranged to determine the position of a heel blank relatively to said knife, means for moving a blank to locate its breast end against said abutment, and means for actuating the knife to remove the corner from the blank while the blank is held against the abutment. 110 115

17. In a lip-cutting machine, the combination of a knife, an adjustable abutment for determining the position of a heel blank relatively to said knife, means for moving a blank to locate its breast end against said abutment, and means for actuating the knife to remove the corner from the blank while the blank is held against the abutment. 120 125

18. In a lip-cutting machine, the combination of a knife, an abutment for supporting a heel blank against the thrust of said knife, a carrier movable from a posi- 130

tion for receiving a blank to a position for locating the blank against said abutment, means for moving the abutment to meet the blank as it reaches the last-mentioned position, and means for actuating the knife.

19. In a lip-cutting machine, the combination of a knife, actuating means therefor, a reciprocating head, a heel blank carrier sustained by said head and movable from 10 a position for receiving a blank to a position for locating the blank in the path of the knife, an abutment arranged to be moved into and out of position for supporting a blank against the thrust of the knife, and means actuated by the head on one movement thereof to turn the carrier for presenting a blank thereon with its breast end in position to engage the abutment and also for moving said abutment against the 20 blank, said means acting to restore said parts to their former positions upon a reverse movement of the head.

20. In a lip-cutting machine, the combination of a knife, actuating means therefor, 25 a reciprocating head, a heel blank carrier having means for engaging a blank, said carrier being pivotally connected with said head, a movable abutment for supporting the blank in position for action thereon by 30 the knife, and means actuated by the movement of said head in one direction for causing the carrier to turn and move a blank from the position in which it was received by the carrier to a position with its breast 35 end horizontal, and for moving the abutment against the blank, said means also acting to restore the carrier and abutment to their original positions upon a reverse movement of the head.

40 21. In a lip-cutting machine, the combination of a knife, an abutment, a carrier arranged to receive a heel blank in one position and to move to another position for locating the breast end of a blank against said 45 abutment, means for actuating the knife to cut a corner from the blank, and means for ejecting the blank from its carrier.

22. In a lip-cutting machine, the combination of a knife, an abutment, a carrier 50 having means thereon to engage a heel blank, means for moving the carrier from position for receiving a blank to position for locating the breast end of the blank against said abutment, means for actuating the 55 knife to cut a corner from the blank, and means for ejecting the blank from its carrier.

23. In a lip-cutting machine, the combination of a knife, a carrier arranged for 60 movement to position a heel blank in the path of said knife, a reciprocating member, an abutment carried thereby, an ejector also carried by said member and arranged for movement relatively thereto, a yielding connection between said ejector and member,

means for arresting the ejector as said member is moved to position the abutment against a blank, and means for actuating the knife and for thereafter releasing the ejector to permit actuation thereof by said 70 yielding connection.

24. In a lip-cutting machine, the combination of a knife, a carrier arranged for movement to position a heel blank in the path of said knife, a reciprocating member, an abutment carried thereby, an ejector also carried by said member and arranged for movement relatively thereto, said ejector having an arm, a yielding connection between 75 said ejector and member, a movable stop in the path of said arm adapted to hold back the ejector against the force of said connection as the abutment is being moved against a blank, and means for actuating said knife and for moving said stop to release the ejector.

25. In a lip-cutting machine, the combination of a knife, a reciprocating head, a carrier sustained by the head and arranged to be actuated thereby to position a heel blank in the path of the knife, a reciprocating member also actuated by said head, an abutment carried by said member, an ejector also carried by said member and arranged for movement relatively thereto, a yielding connection between said ejector and member, means for arresting the ejector as said member is moved to position the abutment against a blank, and means for actuating the knife and for thereafter releasing the ejector to permit actuation thereof by said yielding connection.

26. In a lip-cutting machine, the combination of a knife, a yielding actuator therefor, means for holding said knife against movement by its actuator, a heel blank carrier arranged to position a blank in the path of said knife, a reciprocating member carrying an abutment, an ejector sustained by said member and movable relatively thereto, a yielding connection between said member and ejector, means connected with said knife to arrest the ejector as said member is moved to position the abutment against the blank, means for moving the knife to put its actuator under tension, and means for tripping the knife-holding means to permit said knife to act on the blank and to thereafter release the ejector and permit it to eject the blank.

27. In a lip-cutting machine, the combination of a knife, a yielding actuator therefor, means for holding the knife against movement by its actuator, a reciprocating head, a heel blank carrier sustained by said head, means whereby said head acts on one movement to cause the carrier to locate a heel blank in the path of the knife, a reciprocating member carrying an abutment, an ejector also carried by said member and 130

movable relatively thereto, a yielding connection between said member and ejector, connections whereby said head acts on one movement to cause the carrier to locate a heel blank in the path of the knife and also to move the reciprocating member for positioning said abutment against the blank, means for moving the knife to put its actuator under tension, and means for tripping the knife-holding means to permit the knife to act on the blank and to thereafter release the ejector and permit it to eject the blank, said connections acting to restore the parts to their original positions upon a reverse movement of said head.

28. In a lip-cutting machine, the combination of a knife and actuating means therefor, an abutment to engage the breast end of a heel blank, means for moving the blank into position against said abutment, and means for determining the extent of the bevel produced by the knife.

29. In a lip-cutting machine, the combination of a knife and actuating mechanism therefor, an abutment to engage the breast end of a heel blank, and means for moving the blank into position against said abutment, said abutment and knife having provisions for adjustment on lines parallel with the face of said breast end in order to vary the extent of bevel produced by the knife while maintaining the proper relation of said parts to each other.

30. In a lip cutting machine, the combination with a knife and actuating mechanism therefor, of a reciprocating member, a carrier supported thereby, and an abutment for supporting a heel blank on said carrier in opposition to the cutting movement of the knife, said carrier being movable into one position to receive a blank and into another position to locate the blank against the abutment.

31. In a lip cutting machine, the combination with a knife and actuating mechanism therefor, of a reciprocating member, a carrier supported thereby, an abutment for supporting a heel blank on said carrier in opposition to the cutting movement of the knife, and means for moving said carrier into one position to receive a blank and into another position to locate the breast end of the blank against the abutment.

32. In a machine of the class described, the combination of a reciprocating head, a lip cutting knife and actuating mechanism therefor, a heel blank carrier supported by

the head, and means for actuating the carrier through the reciprocations of the head to cause said carrier to move relatively to said head from a position for receiving a blank into position for presenting the blank to the knife.

33. In a machine of the class described, the combination of a reciprocating head, a heel blank carrier supported by the head, means for actuating the carrier through the reciprocations of the head to cause said carrier to position a blank in the path of the knife, a crank and connections for actuating the head, a lip cutting knife, a spring for actuating said knife, connections with said crank to tension the spring upon one movement of said head, a detent for the knife, and means to trip the detent upon another movement of the head.

34. In a machine of the class described, the combination of a reciprocating head, a heel blank carrier supported by the head and connections to cause the carrier to position a blank in the path of the knife, a crank and connections for actuating the head, a lip cutting knife, a spring connected with said knife, connections including a swinging arm between said crank and knife and arranged to tension said spring upon one movement of the crank, a detent to hold the spring under tension, and means carried by said arm to trip the detent upon another movement of the crank and thereby permit the spring to actuate the knife.

35. In a machine of the class described, the combination with a lip cutting knife, of a reciprocating head, a heel blank carrier movable with said head, and means for automatically moving said carrier relatively to the head, first into position to receive a blank and then into position to locate the blank in the path of the knife.

36. In a machine of the class described, the combination with a lip cutting knife, of a reciprocating head, a heel blank carrier movable with the head, and mechanism actuated by the head for moving said carrier first into position to receive a blank and then into position to locate the blank in the path of the knife.

In testimony whereof I have signed my name to this specification in the presence of two subscribing witnesses.

THOMAS LUND.
